GAFF HOOK

Louis H. Darling, Vallejo, Calif.

Application August 13, 1936, Serial No. 95,935

4 Claims. (Cl. 43—5)

This invention relates to a gaff hook.

The primary object of the invention is to provide a gaff hook that may be folded so that the point of the hook may be held in the handle where it cannot cause injury.

Another object resides in the ease and safety with which the device may be transported. In the folded position the hook may be packed in a space approximately one-half the size ordinarily required to carry such hooks.

Other objects and advantages of the device will become apparent from the description and drawing of the device.

Referring to the drawing:

15 Figure 1 is a front elevation of the device in extended position;

Figure 2 is a side elevation of the same, with the folded position of the hook shown in dotted lines;

20 Figure 3 is a fragmentary sectional view showing the bill of the hook engaged in the handle;

Figure 4 is a fragmentary sectional view on an enlarged scale on the line 4—4 of Figure 1;

Figure 5 is a cross sectional view on the line 5—5 of Figure 1;

Figure 6 is a cross sectional view on the line 6—6 of Figure 1; and

Figure 7 is a detail view on the line 7—7 of Figure 3.

30 Referring more specifically to the drawing, wherein like reference characters designate like or similar parts, the hook 10 has its shaft 10^a secured to a section 11 of the stem, by rivets 12. The section 11 is pivoted to the section 13 by a

35 pin 14. The pin 14 being enclosed by a coil spring 15 having its opposite ends bearing against the section 11 and the section 13 to normally hold the device in an extended position.

The section 13 of the stem extends up into a longitudinal recess 17 in the handle 16, and is secured to the handle by a rivet 18.

The sections 11 and 13 of the stem are channel shaped, the section 11 being smaller than the section 13 so that it fits in the section 13.

45 A sliding catch having a housing 19 is secured by rivets 20 in the channel section 11. The sliding catch having a laterally extending pin 21, sliding longitudinally in a slot 22 in the sides of the section 11, engages in the notches 23 in the opposite sides of the channel section 13. The pin 21 extends through the opposite sides of a U-shaped plate 24. The plate 24 has a button 25 secured to it by a stem 26. The plate 19 has a longitudinal slot 27 for the stem 26 to slide in.

55 A coil spring 28 is attached to the pin 21 and one

of the rivets 20. The button 25, secured to the U-shaped plate 24, being moved longitudinally in the slot 27 moves the pin 21 which passes through openings in the opposite sides of the U-shaped plate 24, against the action of the spring 28, to release the pin 21 from engagement with the notches 23. The notches 23 have inclined lips 23^a to permit the pin 21 to automatically engage the notches 23 against the resistance of the spring 28.

A sliding catch is carried in the recess 17 of the handle 16 and comprises a plate 29 with a V-shaped notch 30 in one end thereof, the opposite end being bent to form a flange 29^a.

The handle 16 has a slot 35 registering with the notch 30 in plate 29 to receive the bill of the hook 10. A button 31 is secured to the plate 29 by a stem 32, and is movable in a slot 33 against the action of a coil spring 34 secured to the section 13 and the flange 29^a, to release the bill of the hook 10 from engagement with the notch 30 of the plate 29.

In operation assuming the device to be in extended position, by pressing the button 25, the U-shaped plate 24 will move the pin 21 in the slot 22 against the action of the spring 28 to release the pin 21 from engagement in the notches 23. The hook can then be moved against the action of the spring 15 to the closed position as shown in Figure 3. To open the device the button 31 is moved longitudinally in the slot 33, against the action of the spring 34, to release the bill of the hook 10 from engagement with the notch 30 of plate 29. The spring 15 will cause the hook to swing to the open position. The pin 21 will slide over the bevelled lips 23^a and engage the notches 23 to hold the device in open position.

I claim as my invention:

1. A folding gaff hook, comprising a handle, a hook, and a stem having two sections pivotally connected together, a sliding catch carried by one of said sections, and cut-away portions in the other section to cooperate with the catch to hold the device rigid when in open position.

2. A folding gaff hook, comprising a hook, a handle, and a stem having two sections pivotally connected together, said handle being hollow to receive a sliding catch, the handle also being provided with an opening to register with the catch, said opening being adapted to receive the point of the hook, said hook being held in folded position by said sliding catch.

3. A folding gaff hook, comprising a handle, a hook, a stem having two sections pivotally connected by a pintle, a coil spring carried by said

pintle, the opposite ends of said spring bearing against the sections to urge the hook to an open position, said handle being hollow to receive a sliding catch to hold the device in folded position, and a latch carried by one of said sections, the other section being provided with recesses to cooperate with the latch, said coil spring normally urging the hook to open position, said latch holding the sections in extended position.

5 10 4. A folding gaff hook, comprising two sec-

tions pivotally connected by a pintle, said pintle carrying a coiled spring, the opposite ends of said spring bearing against the sections to normally urge them to an open position, one of said sections being provided with a sliding catch, and the other section having cut-away portions to cooperate with said catch to hold the sections rigid when in open position.
